UNITED STATES PATENT OFFICE

NATHANIEL M. WHITMORE, OF CAMBRIDGE, MASSACHUSETTS, ASSIGNOR TO HAVERHILL SHOE NOVELTY COMPANY, OF HAVERHILL, MASSACHUSETTS, A CORPORATION OF MASSACHUSETTS

FASTENING MEANS

Application filed July 2, 1929. Serial No. 375,538.

This invention relates to connectible and disconnectible fastening means of the type adapted to connect straps, or similar flexible members, and it is especially adapted for the connection of straps which are fixedly secured to the opposite sides of a shoe, for example as distinguished from those straps which are free to slide. An object of this invention is to improve the construction of fastening means of the type described.

When straps which are fixedly secured to an article are connected it will be obvious that the final position, which the fastening employed will assume after the straps have been pulled taut and fastened together, will depend upon the contour and the dimensions of the object embraced by the straps. While this final position may be readily determined for any given object, it is often necessary to provide straps for embracing objects which may vary in size, and in this event, it will be clear that the final position of the fastening will vary with the size of the object. Although this variation may be relatively slight in many cases, it is frequently quite important that the fastening take a certain definite position. This becomes necessary in some instances in order that the fastening may be accessible, while in other cases, and especially where the fastening is used with articles of wearing apparel, ornamental jewelry, or wherever the fastening itself serves as an ornament, it is usually particularly important that the fastening be in a certain definite position.

It is a more particular object of this invention, therefore, to provide relatively fixed straps with a connectible and disconnectible fastening capable of holding the straps taut and embodying means for adjustment of the fastening relative to the straps so as to assure that the fastening will occupy a definite, predetermined position after the straps have been connected.

This and other objects are effected by my invention, as will be apparent from the following description and claims taken in connection with the accompanying drawings forming a part of this application, and in which:

Figs. 1, 3, and 5 are face views of different types of buckles, the straps for the respective buckles being shown in position for insertion;

Figs. 2, 4, and 6 are, respectively, longitudinal sections through the buckles shown in Figs. 1, 3, and 5, showing the straps in position in the respective buckles; and

Fig. 7 is a perspective view of a shoe.

In accordance with the present invention a main buckle is provided with an auxiliary fastening means, which is, preferably, an auxiliary buckle arranged to be adjustable lengthwise of one of the straps, and to be capable of securely connecting the main buckle to such strap. In this way it is possible definitely to locate the main buckle in any desired position with respect to the object embraced by the straps, and, once this position has been ascertained and the auxiliary buckle properly adjusted, it is merely necessary to fasten the main buckle in the usual manner.

In Figs. 1 and 2 the main buckle 10 is of a familiar type and comprises the rectangular frame 11 having a cross-bar 12 arranged transversely and extending between the side members of the frame 11. The bar 12 has a reduced central portion 13 which provides a journal for the eye 14 of the buckle bar 15. The end portions of the bar 12 are also reduced to provide journals 16 for the spaced eyes 17 of the auxiliary buckle 18. This auxiliary buckle is rectangular in form and has a cross-bar 19 arranged transversely between the side members of the frame and equally spaced from the ends thereof to provide suitable recesses for receiving the strap 20. The cross-bar 19 is, preferably, so arranged with respect to the end members of the buckle 18 as to cause the strap to take a rather sharp bend as it passes over this cross-bar and under the end members of the frame. In this way it is assured that the strap 20 will be firmly held by the auxiliary buckle 18, and by virtue of the pivotal connection of this auxiliary buckle to the bar 12 of the main buckle it is possible, by merely rotating the auxiliary buckle slightly on this pivotal connection, to remove, or to in-

sert the strap 20, and at the same time it is assured that when the auxiliary buckle is in its operative position, as shown in Fig. 2, the strap 20 will be firmly held therein.

5 After the buckle has been adjusted in the manner just described to the desired position with respect to the strap 20, the strap 21 is inserted in the main buckle and the buckle bar 15 engaged in one of the eyes 22 of the strap 21 in the usual manner.

10 It will be observed that in this modification, both the main buckle 10 and the auxiliary buckle 18 are convexo-concave in form, and that the concave sides of the respective buckles are arranged adjacent to each other. This has been found to be a desirable arrangement as it provides a suitable space beneath the strap 21 for receiving that portion of the strap 20 which lies directly above the bar 19 of the auxiliary buckle, and thus, provides a compact arrangement which permits the main buckle to remain in its operative position. It will also be observed that the eyes 17 of the auxiliary buckle 18 are disposed substantially on the concave side of the auxiliary buckle, so that the axis, about which the auxiliary buckle is rotatable with respect to the main buckle, is disposed on the concave side of the buckle. This feature also contributes to the compactness of the device in that it permits the auxiliary buckle to be folded closely adjacent to the main buckle, and at the same time provides a suitable space between the two buckles and the strap 21 for that portion of the strap 20 which lies directly above the bar 19. Furthermore as the auxiliary buckle is approximately half the length of the main buckle and is also mounted to pivot about an axis disposed approximately midway between the ends of the main buckle, it will be evident that the auxiliary buckle is adapted to be swung to a position in which its free end lies closely adjacent the end of the main buckle as shown. In this position the free end of the auxiliary buckle may cooperate with the adjacent end of the main buckle to produce a gripping action on the interposed strap 21.

15 In Figs. 3 and 4 the main buckle 25 has a rectangular frame 26 which is substantially flat and extending between the sides of this frame, and intermediate the ends thereof is a bar 27 which is provided with journals 28 adjacent the side members for receiving the eyes 17 of the auxiliary buckle 18. The central portion of the bar 27 is provided with longitudinally extending tongues 29 for the purpose of reducing the space between the end members of the frame 26, so that the strap 21 may be passed under one end member, over the bar 27 and under the other end member and be held frictionally in the buckle in this manner. The arrangement of the auxiliary buckle 18 and of the strap 20 therein

is, in all respects, similar to that described with reference to Figs. 1 and 2.

The buckle 31, shown in Fig. 5, has a rectangular frame 32 which is convexo-concave and is provided with suitable recesses 33 extending transversely across the body of the buckle adjacent the respective ends thereof for the purpose of receiving the strap 21' to engage the same frictionally in the manner described with reference to Figs. 3 and 4. 70 In the central portion of the buckle, adjacent the sides thereof, suitable journals 34 are provided by stamping, or otherwise forming suitable recesses 35 in the body of the buckle. 75

The journals 34 receive the eyes 17 of the auxiliary buckle 18 and thus provide a pivotal connection for the auxiliary buckle in the same manner as described with reference to the other figures. The auxiliary buckle in this instance is similar to the auxiliary buckle 18 shown in the other figures of the drawings.

80 The advantages of this construction become more apparent when it is considered in connection with straps fixedly secured to some article, such, for example, as the shoe 38 of Fig. 7. This shoe is provided with a buckle 10 of the type shown in Fig. 5, although, of course, any of the types of buckles just described or other similar buckles might be used if desired. It is well known that it is frequently necessary to move a buckle 10 one way or another on the strap 20 in order to assure that the buckle will be properly centered and occupy the correct position after the strap 21 is fastened. This may be accomplished with any of the buckles disclosed by merely effecting the proper adjustment of the strap 20 with the auxiliary buckle 18, and in this way it is possible to avoid the inconvenience as well as the loss of time and additional labor involved in resetting a buckle of the usual type. 95

100 While several forms of this invention have been shown and described, it will be obvious that various modifications thereof will occur to those skilled in the art to which the invention appertains, and it will be understood that the invention is not limited except as indicated by the appended claims.

110 I claim:

1. In a buckle for use on straps fixedly secured at their ends to opposite sides of the closure slit of an article for centering the buckle, a main buckle frame comprising side and end members, the main buckle frame having strap-receiving openings adjacent the end members so that a strap may be passed through these openings and under each of the end members, means for releasably securing a strap in the main buckle frame, a concavo-convex auxiliary buckle of approximately half the length of the main buckle frame, the auxiliary buckle being mounted to pivot on the main buckle frame about an axis disposed 120

transversely of this frame and approximately midway between the ends thereof so that the auxiliary buckle may swing with its concave side adjacent the main buckle frame to a position wherein the free end of the auxiliary buckle is disposed adjacent an end of the main buckle frame, the auxiliary buckle having transverse slots for receiving and frictionally holding a strap.

10 2. In a buckle for use on straps fixedly secured at their ends to opposite sides of the closure slit of an article for centering the buckle, a main buckle frame comprising side and end members, the main buckle frame having strap-receiving openings adjacent the end members so that a strap may be passed through these openings and under each of the end members, means for releasably securing a strap in the main buckle frame, a

15 concavo-convex auxiliary buckle of approximately half the length of the main buckle frame, the auxiliary buckle being mounted to pivot on the main buckle frame about an axis disposed transversely within this frame approximately midway between the ends thereof, this axis also being disposed on the concave side of the auxiliary buckle so that the latter may swing with its concave side adjacent the main buckle frame to a position

20 wherein the free end of the auxiliary buckle is disposed closely adjacent an end of the main buckle frame, the auxiliary buckle having transverse slots for receiving and frictionally holding a strap, these slots being

25 closely spaced to form a relatively sharp bend in the strap secured therein so that this bend may be disposed in the space between the concave side of the auxiliary buckle and the main buckle frame and provide a compact

30 nested arrangement of main and auxiliary buckles.

Signed by me at Boston, Massachusetts,
this 26th day of June, 1929.

NATHANIEL M. WHITMORE.
